UNITED STATES PATENT OFFICE.

WILLIAM ROBERT REED, OF TORONTO, ONTARIO, CANADA, ASSIGNOR OF ONE-HALF TO
ALBERT WELCH, OF TORONTO, ONTARIO, CANADA.

COMBINED ASH SIFTER AND RECEPTACLE.

1,271,223.

Specification of Letters Patent. Patented July 2, 1918.

Application filed November 27, 1917. Serial No. 204,179.

To all whom it may concern:

Be it known that I, WILLIAM ROBERT REED, a subject of the King of Great Britain, residing at the city of Toronto, in the county of York and Province of Ontario, Dominion of Canada, have invented certain new and useful Improvements in Combined Ash Sifters and Receptacles; and I hereby declare that the following is a full, clear, and exact description of the same.

My invention relates to improvements in ash-sifters, and more particularly to one of a stationary character.

The principal objection which obtains in practically all the forms of ash-sifters now in general use, is that no adequate provision is made for arresting and removing the dust which arises from the necessary agitation of the ashes during the dumping and sifting action.

The object of my present invention is to combine with my general structure, suitable means for taking up and removing the dust, and to that end, my invention consists broadly of a casing for the reception of the ashes having an unobstructed open front and closed upper side and rear walls, and a draft-passage connecting the interior of the casing with the draft-flue of the chimney.

My invention further consists of certain details in the general structure, all of which will be fully hereinafter described and pointed out in the claims.

In the drawings:—

Figure 1, is an isometric view of the casing and its connection with the chimney;

Fig. 2, is a front elevation of the casing, showing the shaker and pan in position; and,

Fig. 3, is a separate view of the shaker.

Referring to the drawings, it will be seen that the casing, for the reception of the ashes, comprises two side walls 1, 1, and the rear wall 2, preferably formed from a single metal sheet, bent at right-angles, as shown.

The top wall consists of the rear, stationary section 3 and the front, hinged section 4, having side-retaining angular flanges 5, and front-retaining flange 6, these flanges serving to hold the hinged section 4 in closed position.

A lifting handle 7 is provided, which is secured along the front edge of the hinged section 4. Upon the inner surfaces

of the side walls 1, 1, are secured the angular ways 8, 8.

9 is the sifting receptacle, of rectangular form, provided with the wire-cloth bottom 10, of suitable mesh, and the side flanges 11, 11, which rest in sliding engagement with the angular ways 8, 8, within the casing. 12 is a handle upon the front wall of the sifting receptacle 9. A pan 13 is provided for catching and removing the finer material which falls from the sifting receptacle.

14 is the pipe or draft-passage connecting the interior of the casing with the draft-flue of the chimney 15, and 16 is a damper for opening and closing the draft passage 14.

In operation, the sifting receptacle is placed in position upon the ways 8, 8, and the hinged section 4 is raised and thrown back to facilitate the deposition of the ashes within the sifting receptacle. The hinged section 4 is then dropped into closed position, ready for the separating action of the sifting receptacle, and the damper 16 in the draft-passage 14 is then opened, causing a strong current of air to enter the unobstructed open front of the casing and pass therethrough into the draft-passage 14 and up the draft-flue of the chimney, carrying with it all of the dust within the chamber, arising from the ashes during the sifting action.

To increase the suction of air through the casing and into the draft-flue of the chimney, the casing may be raised from the floor and placed upon loose supports, which will result in giving an unobstructed open bottom, in addition to the unobstructed open front, thereby increasing the power of suction through the casing, to a maximum degree of efficiency.

With my improved open construction, I am enabled to take advantage of the entire and unobstructed force of suction through the casing and into the draft-flue of the chimney, thereby avoiding the nullifying effect upon the draft, which obtains with the closed formation of casing now in general use.

When it is desired to use the device simply as a receptacle for the ashes, all that is necessary, is to remove the sifting receptacle and

deposit the ashes in the pan 13, and all dust arising from such action is carried by the suction, up and through the draft-passage 14 and into the draft-flue of the chimney.

5 It will be seen that the absence of a front wall and a floor plate, reduces to a minimum, the amount of metal required, as well as the cost of assembling the parts.

The form of connection with the draft-flue does not interfere with the drawing power of the chimney, as the damper 16 can be instantly closed when the sifting action is completed. The draft-passage 14 can, if desired, be connected directly to the smoke-

15 pipe of the furnace.

During the months when the sifter is not required, it can be quickly disengaged from the draft-passage or smoke-pipe of the furnace, and moved away until again needed.

Copies of this patent may be obtained for five cents each, by addressing the "Commissioner of Patents,

Having thus fully described the nature of 20 my invention, what I claim as new and desire to secure by Letters Patent, is:—

1. A casing for the reception of the ashes having an unobstructed open front and closed upper side and rear walls, and a 25 draft-flue connecting with the interior of the casing to carry off the dust therefrom.

2. A casing for the reception of the ashes having an unobstructed open front and bottom and closed upper side and rear walls, 30 and a draft-flue connecting with the interior of the casing to carry off the dust therefrom.

Toronto, November 12th, 1917.

WILLIAM ROBERT REED.

Signed in the presence of—

EDWARD V. BERNSTEIN,

W. T. MILLER.
